United States Patent

Des. 241,675

Patented Sept. 28, 1976

241,675

DISPERSING APPARATUS

Donald M. Schnear, Corona del Mar, Calif., assignor to
Morehouse Industries, Inc., Fullerton, Calif.

Filed Oct. 16, 1974, Ser. No. 515,263

Term of patent 14 years

Int. Cl. D15—99

U.S. Cl. D15—122

FIG. 1 is a top perspective view of the dispersing apparatus; and

FIG. 2 is a bottom perspective view of the apparatus of FIG. 1 showing the other end of the bridge member.

I claim:

The ornamental design for a dispersing apparatus, as shown and described.
